CLAIM

The ornamental design for a pick-up bed storage unit, as shown and described.

DESCRIPTION

FIG. 1 is a diagrammatic perspective view of a pick-up bed storage unit, with one drawer open, in full lines with a pick-up truck shown in broken lines representing environmental association matter being for illustrative purposes only and forming no part of the claimed invention;

FIG. 2 is a diagrammatic perspective view of the pick-up bed storage unit with the drawer shown in closed position;

FIG. 3 is a front elevational view of FIG. 2;

FIG. 4 is a rear elevational view of FIG. 2;

FIG. 5 is a top plan view of FIG. 2;

FIG. 6 is a bottom plan view of FIG. 2;

FIG. 7 is a left side elevational view of the pick-up bed storage unit of FIG. 2; and,

FIG. 8 is a right side elevational view of FIG. 2.

The surface(s) or portion(s) of the article not shown in the drawing or described in the specification form(s) no part of the claimed design.
